United States Patent Office.

JOSEPH G. BICKNELL, OF CAMBRIDGEPORT, MASSACHUSETTS.

Letters Patent No. 70,155, dated October 29, 1867.

IMPROVED WINDOW-SCREEN.

The Schedule referred to in these Letters Patent and making part of the same.

TO ALL WHOM IT MAY CONCERN:

Be it known that I, JOSEPH G. BICKNELL, of the city of Cambridgeport, county of Middlesex, and State of Massachusetts, have invented a new and original plan for Window-Screens or Mosquito-Frames; and I do hereby declare that the following is a full and exact description thereof, reference being had to the accompanying drawings, and to the letters of reference marked thereon.

The nature of my invention consists in covering the whole window, from the top to the bottom, so as to effectually exclude mosquitoes or flies, and at the same time have the window open at the top or bottom, as the occupant of the room may desire.

In order to do this I make a frame to cover the whole window-sash; this I call an outside frame, and is marked A in the drawings. I next make an inside frame, of three pieces of wood, of one-half of the size of the outside frame, or smaller, as the case may require, and hang it with hinges, or by putting screws through the top end of each upright bar into the outside frame. From the top ends of this frame I nail some small pieces of wood round the inside of the outside frame, to nail the netting to, and to hang the bottom frame to when hinges are used; thus, showing the outside frame all round, it will be readily seen that this bottom or inside frame will open readily to enable a person to open a window or blinds easily, or to close the same. This inside frame is marked B in the drawings, and if wanted to be kept open it may be by putting a catch, G, on the top or side of the frame, or by a cord, M, and hook N, as shown in the drawings. H, hinges; S, spring-catch to hold the opening frame together when closed; K, knob; r, screws by which the frame is fastened to the window.

Sectional drawing No. 2 represents a screen-frame with smaller openings, to be used in places where there is not room to swing one-half of the screen-frame into the room. I make these small openings to enable any one to open or shut blinds or windows with ease, and keep the screen in the window. At the same time it will be useful to have two of these openings in most frames, viz, one at the bottom to open blinds through, and one near the centre of the frame to unfasten the sash from. The same letters of reference apply to this as to the other.

Claim.

I claim the combination of the outer frame A with the inner netting-covered frame B, fitted into it and hinged at its sides, all as and for the purpose described.

JOSEPH G. BICKNELL.
